CLAIM

The ornamental design for a combined eye shade and ear protector, as shown and described.

DESCRIPTION

FIG. 1 is a front perspective view of a combined eye shade and ear protector showing my new design;

FIG. 2 is a right side elevational view, the opposite side being a mirror image thereof;

FIG. 3 is a front elevational view thereof;

FIG. 4 is a top view thereof;

FIG. 5 is a rear elevational view thereof;

FIG. 6 is a bottom plan view thereof; and

FIG. 7 is a front perspective view of a modified form of the combined eye shade and ear protector shown in FIG. 1.

The broken line showing of a face and head in FIGS. 1 and 2 is for illustrative purposes only.

*FIG. 1.**FIG. 2.**FIG. 3.**FIG. 4.**FIG. 5.**FIG. 6.**FIG. 7.*
